The ornamental design for a optical fiber cleaver, as shown and described.

DESCRIPTION

FIG. 1 is a front, left, top perspective view of a optical fiber cleaver showing my new design;

FIG. 2 is a front, right, top perspective view thereof;

FIG. 3 is a rear, right, top perspective view thereof;

FIG. 4 is a front, right, bottom perspective view thereof;

FIG. 5 is a rear, left, bottom perspective view thereof;

FIG. 6 is a front elevational view thereof;

FIG. 7 is a rear elevational view thereof;

FIG. 8 is a right side view thereof;

FIG. 9 is a left side view thereof;

FIG. 10 is a top plan view thereof; and,

FIG. 11 is a bottom plan view thereof.

The broken line showing is for the purpose of illustrating portions of the article and forms no part of the claimed design.
